[57] CLAIM

The ornamental design for a liquid aerator, as shown and described.

DESCRIPTION

FIG. 1 is a side elevational view of a liquid aerator showing my new design, the opposite side being a mirror image except for the lack of a square knob;

FIG. 2 is a top plan view thereof;

FIG. 3 is a rear elevational view thereof;

FIG. 4 is a front elevational view thereof; and

FIG. 5 is a bottom plan view thereof.
